(57) **CLAIM**

The ornamental design for a wine dispenser and preserver, as shown and described.

DESCRIPTION

FIG. 1 is a perspective view of a wine dispenser and preserver showing the new design.

FIG. 2 is an installed perspective view of the wine dispenser and preserver shown in a configuration of use.

FIG. 3 is an exploded perspective view of the wine dispenser and preserver shown in a configuration of use.

FIG. 4 is a front view of the wine dispenser and preserver of FIG. 1.

FIG. 5 is a rear view of the wine dispenser and preserver of FIG. 1.

FIG. 6 is a side view of the wine dispenser and preserver of FIG. 1.

FIG. 7 is an opposite side view the wine dispenser and preserver of FIG. 1.

FIG. 8 is a top view the wine dispenser and preserver of FIG. 1; and,

FIG. 9 is a bottom view the wine dispenser and preserver of FIG. 1.

The dashed lines in the drawings are shown for the purpose of illustrating both parts of the wine dispenser and preserver as well as environmental structure. None of the dashed lines form part of the claimed design.
